UNITED STATES PATENT OFFICE.

ELWIN L. THOMPSON, OF BALDWINSVILLE, MASSACHUSETTS.

FOLDING GO-CART.

SPECIFICATION forming part of Letters Patent No. 782,930, dated February 21, 1905.

Application filed September 24, 1904. Serial No. 225,732.

To all whom it may concern:

Be it known that I, ELWIN L. THOMPSON, a citizen of the United States, and a resident of Baldwinsville, in the county of Worcester and State of Massachusetts, have invented an Improvement in Folding Go-Carts, of which the following description, in connection with the accompanying drawings, is a specification, like characters on the drawings representing like parts.

This invention has for its object the production of a novel folding go-cart so constructed and arranged that while of light weight, strong and simple, and quickly and readily foldable into a compact form for transportation or storage it possesses great resiliency and flexibility so far as concerns the comfort of the occupant, with the strength and durability requisite for safety when in use.

In the present embodiment of my invention the body, comprising seat, back, and arms, is pivotally mounted upon and connected with the running-gear, the latter including wheels, their axles, and spring side bars connecting them. I make the running-gear non-collapsible, and thus independent of the folding action, so that its strength is very materially increased and the resiliency of the spring members thereof is distributed in a better manner and with greater ease to the occupant than is compatible with collapsing or foldable running-gear.

The various novel features of my invention will be fully described in the subjoined specification and particularly pointed out in the following claims.

Figure 1 is a side elevation of a go-cart embodying one form of my present invention in upright position. Fig. 2 is a longitudinal sectional detail, enlarged, taken through the center of the seat. Fig. 3 is a side elevation of the go-cart in folded position. Fig. 4 is a side elevation of a modification of the go-cart in upright position. Fig. 5 is a back view thereof; and Fig. 6 is a side elevation of the modification, showing the go-cart folded in full lines, an intermediate position assumed during the folding being indicated by dotted lines.

I have herein shown the running-gear as

non-collapsible and comprising front and rear axles a^x b^x , of suitable construction, equipped, respectively, with wheels A B (the latter being shown as of considerably larger diameter) and fore and aft spring members or side bars c . These side bars are made of strong yet light spring metal and are continuous from end to end and fixedly secured at their opposite ends to the axles, the spring or resilience of the side bars being increased at the back of the vehicle by bending them to form C-springs c^x . The main portions of the side bars are well above the axles and substantially horizontal, as shown in Figs. 1, 3, 4, and 6, and their front ends are bent down at c' to the axle a^x , a foot-rest f being attached by brackets f' to the parts c' . A skeleton running-gear is thus formed, strong, light, yet possessing great resiliency for the proper and comfortable support of the body of the go-cart.

Referring to Figs. 1, 2, and 3, the side bars have rigidly secured thereto near the front ends of their horizontal portions depending ears c^2 and rigid upturned ears c^3 above the C-springs. The back of the body and the seat h' are pivotally connected at h^x , the lower ends of the handle-bars h of the back extending below the seat and having ears h^2 rigidly secured thereto and forwardly extended. Pivots h^3 connect the handle-bars with the upturned ears c^3 of the running-gear, so that the back can swing between the side bars c on the fulcra h^3 when the go-cart is folded or unfolded. The depending ears c^2 have fulcrumed thereon at h^4 upturned arms h^5 , connected at their upper ends by a cross-bar h^6 , which swings below the seat h' and supports the latter at its front end (see Figs. 1 and 2) when the go-cart is unfolded. Links h^7 are pivotally connected with the ears k^2 on the handle-bars and with the arms h^5 at h^8 , so that the arms will swing on their fulcra h^4 oppositely to the back when it is swung on its fulcra h^3 . A locking stud or keeper h^9 in the bottom of the seat is adapted to cooperate with the cross-bar h^6 when the body is in upright position, and a guard h^{10} extends beneath the seat fore and aft to limit the swinging movement of the arms h^5 . Side arms h^{11} are fulcrumed at h^{12} on the handle-

bars h and pivotally connected near their front ends with links h^3 , fulcrumed at h^4 on the sides of the seat.

The lower ends of the handle-bars act as links and with the arms h^5 constitute a pivotal or swinging connection between the body and the running-gear, the weight of the occupant being transmitted through such connection to the spring side bars c , as will be manifest.

When the cross-bar h^6 is held between the front end of the guard h^{10} and the keeper h^9 , as in Figs. 1 and 2, the body is locked from swinging movement with relation to the running-gear and can only be unlocked by lifting the front end of the seat h' far enough to cause the stud or keeper to clear the cross-bar. Then to fold the go-cart into small compass for carrying it about or for storage when not in use the upper end of the back is swung forward in the direction of arrow 75, Figs. 1 and 2. The links h^7 are then pulled back, causing the arms h^5 to swing rearward on their fulcra h^4 in the direction of arrow 76, Fig. 2, the arms being extended between the side bars c of the running-gear. As the forward swing of the back is continued it folds down upon the seat, the links h^3 acting simultaneously to swing the side arms up against the handle-bars h of the back; but at the same time the backward swing of arms h^5 on their fulcra h^4 carries the cross-bar h^6 along the guard to the rear end thereof, permitting the front of the seat h' to descend until the ends of the links h^3 rest at their pivotal points h^4 upon the side bars, as shown in Fig. 3. In such folded position the go-cart is manifestly very compact and occupies very little room, so that it can be carried about readily or hung up out of the way when not in use.

During the folding operation the connection-points h^8 between the links h^7 and arms h^5 gradually approach a straight line between the relatively fixed fulcrum-points h^3 h^4 , and the length of the links h^7 is such that just before final folded position is reached the points h^8 are caused to snap below the straight line between said relatively fixed fulcra, locking the body in folded position. This snap or jump is permitted by the resiliency of the side bars c , so that when the go-cart is completely folded, as in Fig. 3, the parts will be retained folded until a hard enough pull is given the back away from the running-gear to overcome the resiliency of the side bars c and permit the points h^8 to snap back past dead-center on the upper side. Then the unfolding is completed by returning the back and seat to the position shown in Figs. 1 and 2, the stud h^9 being inclined and provided with a rounded end to let the cross-bar h^6 pass beneath it to locking position. The swinging arms and cross-bar thus act not only to support the front end of the seat, but also as a latch device to lock the body in upright position.

In the modified construction shown in Figs.

4, 5, and 6 the running-gear is the same; but the back and seat b b' of the body are relatively fixed and conveniently made of bent wood, the seat being curved over and down in front at b^2 to form a support for the legs of the occupant. Truss-braces b^3 , made of rigid iron straps, are secured to the under side of the seat b' and its curved front b^2 , the rear ends of the braces being attached to the lower ends of the handle-bars h , secured to the back b . Upturned ears 1 are secured to the side bars about the center of the horizontal portions thereof, and similar ears 2 are attached at the front ends of such portions. Depending links 3 are rigidly attached to the body beneath the seat, their lower ends being fulcrumed at 4 on the ears 1, the links extending between the said ears and forming a pivotal or swinging connection between the body and the running-gear, the weight of the occupant being transmitted by the supporting-links directly to the spring side bars c . The seat is made of less width than the distance between the side bars, so that it can be swung between them when the body is folded onto the running-gear, as will be explained. Side arms b^4 are pivotally connected with the body, herein shown as fulcrumed at 5 on the handle-bars h , and long links 6 are pivoted at 7 to the arms near their outer ends, the lower ends of said links being fulcrumed at 8 on the ears 2.

In order to hold the body locked from swinging movement with relation to the running-gear, I have provided latch members d , fulcrumed at 9 on the links 3 and having notches 10 11 in their lower edges near their outer ends, a cross-bar d^x connecting the members d . A rod d' , secured to the side bars c and extended from one to the other below the latch members, serves as a keeper, the notches 10 11 cooperating therewith, said latch members swinging between the side bars, a spring s^x , attached at its ends to the axle b^x , and cross-bar d^x , holding the latch members and keeper in engagement. When the notches 10 engage the keeper, the links 3 are held from angular movement and the body is maintained locked in upright position, but permitting free movement of the body with the spring action of the side bars, the latch members d at such time assisting to support the weight of the body and its occupant.

To fold the go-cart, the cross-bar d^x is lifted, releasing the members d from the keeper, and the body is swung forward bodily on the pivots 4 as fulcra, the dotted lines in Fig. 6 showing the movement, and as such movement is continued the seat swings down behind the foot-rest f and between the side bars into full-line position, Fig. 6. At such time the notches 11 receive the keeper d' and the body and running-gear are locked in such position. While the body is being moved into folded position, the links 6 swing on their fulcra 8 and turn 130

the side arms b^4 toward the back of the body, as shown in Fig. 6. The go-cart can then be turned into a vertical position, resting on the rear wheels B, and either leaned against the 5 wall or hung up or carried about by the top bar h^{2x} of the handle.

To restore the go-cart to position for use, the latch is released and the body and running-gear will swing apart until the spring 10 s^x causes the notches 10 to engage the keeper, and the body is then locked in upright position.

My invention is not restricted to the precise construction and arrangement shown and 15 described, as the same may be modified or varied in different particulars without departing from the spirit and scope of my invention.

Having fully described my invention, what 20 I claim as new, and desire to secure by Letters Patent, is—

1. In a folding go-cart, running-gear, including continuous spring side bars, a body pivotally connected therewith, whereby the 25 running-gear and body may be folded together, and means acting automatically by opening or folding of the body, respectively, to lock the body in upright or in folded position.

2. In a folding go-cart, running-gear, including continuous elastic side bars bent to 30 form C-springs at their rear ends, a body, link connections between it and the side bars, and a latch to lock the body in upright position while permitting it to move in unison 35 with flexure of the side bars.

3. In a folding go-cart, running-gear, including front and rear axles and their wheels, continuous spring side bars fixedly connected at their ends with the axles, and bent to form 40 C-springs at their rear ends, a body, pivotal connections between it and the running-gear, whereby the body may be folded down upon the running-gear, and means to lock the body in upright position.

4. In a folding go-cart, running-gear, including continuous spring side bars, an attached foot-rest, a body pivotally connected with the side bars and adapted when folded to swing between them, and means automatically operative by opening or folding of the body, respectively, to lock the body in upright or in folded position.

5. In a folding go-cart, running-gear, including continuous spring side bars, a foot-rest fixedly mounted thereon, a body pivotally connected with the side bars, arms jointed to the body, means to automatically move the arms toward the back of the body when the latter is swung into folded position, and means 55 to lock automatically the body in upright or in folded position.

6. In a folding go-cart, non-collapsible running-gear having fore and aft continuous spring members, a body pivotally connected

with and supported by said members, and 65 adapted to be swung down upon them when folded, and means, comprising a swinging, automatically-controlled latch member and a keeper, to lock the body from swinging movement relatively to the running-gear. 70

7. In a folding go-cart, non-collapsible running-gear having fore and aft continuous spring members, a body having a back, and side arms jointed thereto, means to automatically fold the side arms against the back when 75 the body is folded upon the running-gear, swinging members pivotally connecting said body with the spring members of the running-gear, and means to lock automatically the body and prevent angular movement of 80 said swinging connecting members relatively to the spring members of the running-gear.

8. In a folding go-cart, non-collapsible running-gear having fore and aft spring members bent to form C-springs at their rear end, a 85 body, supporting-links connected therewith and fulcrumed on the running-gear, a latch member pivotally connected with the running-gear, a keeper mounted on the body, and means to automatically move the latch member 90 into position to coöperate with the keeper and lock the body in upright position.

9. In a folding go-cart, non-collapsible running-gear, including spring side bars, a body having a relatively movable back and seat, 95 pivotal connections between said body and running-gear, whereby the back may be swung down upon the seat and the seat upon the side bars, a keeper mounted on the seat, and a swinging latch fulcrumed on the side bars and 100 adapted to coöperate with the keeper to maintain the body in upright position.

10. In a folding go-cart, non-collapsible running-gear having fore and aft spring members, a foot-rest fixed thereon, a body having a pivotally-connected back and seat and swinging side arms, links pivotally connected with the latter and the seat, the back below the pivotal connection with the seat being fulcrumed on the spring members, and manually-released locking means to prevent angular movement of the body relatively to the spring members of the running-gear, the seat swinging down behind the foot-rest and the side-arm links resting upon the spring members when the body is moved into folded position. 115

11. In a folding go-cart, running-gear, including continuous spring side bars, a body comprising a back and a pivotally-connected seat, fixed upright ears on the side bars, on 120 which the back is fulcrumed below the seat, depending ears fixed on the side bars near the front ends thereof, upturned arms fulcrumed on said ears and having a connecting cross-bar at their upper ends, constituting a latch movable beneath the seat, a coöoperating keeper on the seat, whereby the body is locked in upright position, and links pivotally connecting 125

the swinging arms with the back below its fulcrum, the points of connection between the links and the arms snapping past dead-center with relation to the fulcra of the back and arms when the body is folded to retain the same in folded position.

5 In testimony whereof I have signed my name

to this specification in the presence of two subscribing witnesses.
